Oscar Geier

UNITED STATES PATENT OFFICE.

LORENZ SOSDIAN, OF NEW YORK, N. Y.

TOOTH-BRUSH.

1,325,268.

Specification of Letters Patent.

Patented Dec. 16, 1919.

Application filed July 1, 1918. Serial No. 242,777.

To all whom it may concern:

Be it known that I, LORENZ SOSDIAN, a subject of the King of Hungary, residing at New York, county of New York, and State 5 of New York, have invented certain new and useful Improvements in Tooth-Brushes, of which the following is a specification.

This invention relates to improvements in tooth brushes and particularly to types 10 adapted to carry a supply of dentifrice in a powder or paste form.

The principal object of the invention is to provide a tooth brush having a hollow handle adapted to contain a quantity of denti- 15 frice in a powder or paste form, the same being so arranged as to be conveyed to the bristles of the brush at any required time.

A further object is to provide means whereby a spring pressure is applied to the 20 material so that the same may be unfailingly fed through the handle portion of the brush and finally to provide means which will prevent the feeding of the dentifrice at such time as it is not required.

25 These and other like objects are attained by the novel construction and combination of parts hereinafter described and shown in the accompanying drawings, forming a material part of this disclosure, and in which:—

30 Figure 1 is a perspective view showing a tooth brush made in accordance with the invention.

Fig. 2 is a longitudinal sectional view taken through the center line of the same.

35 Fig. 3 is a fragmentary horizontal sectional view taken on line 3—3 of Fig. 2, and

Fig. 4 is an enlarged transverse sectional view taken on line 4—4 of Fig. 2.

In carrying out the invention use is made 40 of a substantially cylindrical handle 10, having at its outer end a knurled cap 11, engaged by screw-threads 12, and provided with an inner extending point 14, guiding the outer end of a helically coiled compres- 45 sion spring 15, its opposite end pressing against a plunger 16, free to slide within the tubular handle.

The opposite end of the handle is integrally formed with a solid head 18, having 50 a threaded stem 19, engageable with the brush backing 20, from which extend on one side the bristle tufts 22 in the usual manner.

Formed through the head 18 is an open- 55 ing 24 communicating with a similar elongated opening 25, in the backing 20, and ex- tending from the opening 25 are a plurality

of transverse passages 26 reaching nearly to the edge of the brush backing and communicating with opening 25 through openings 27, extending downwardly so as to enter be- 60 tween the bristle tufts 22.

Formed transversely through the head 18 is a bored opening 30 in which is operatively engaged a plunger 31, pressed normally upward by a coiled compression spring 32, 65 held in operative position by a screw-threaded plug 33, entered in the bottom of the opening 30.

Formed with the plunger 31 is a plunger rod 35, and secured on the rod 35 is a collar 70 36, having an extending key 37, while in the outer end of the plunger rod 35 is an actuating knob 38, the key being engageable in a key-way 39 formed in the head.

From the foregoing it will be understood 75 that the plunger 31 is adapted to be pressed outwardly into position to close the passage through the opening 24 by the spring 32, and that the plunger may be depressed by actuating the head 38 in an obvious manner. 80

If it is desired, however, to maintain the plunger in an extended position, as when the brush is not in use, by rotating the knob 38 the key 37 may be so positioned as to rest against the outer surface of the head 18 as 85 shown in Fig. 2, thereby preventing any of the material held within the reservoir or tubular casing 10 from entering into the passage 24 and passing into the brush, the plunger acting as a valve in controlling the 90 passage.

In filling the device, the knob 11 is unscrewed, the spring and plunger removed, and a desired quantity entered into the cylindrical reservoir, whereupon the plunger 95 16 is inserted so as press the material toward the front of the apparatus by the action of the spring 15 which is held in operative position by the head 11.

From the foregoing it will be seen that 100 a convenient device has been shown in which a tooth brush may be supplied with any quantity desired of material carried within the tubular handle element.

The construction is of a simple character, 105 comprised of two parts, the operation of which will be evident from the foregoing, taken in connection with the drawings.

Having thus described my invention what I claim as new and desire to secure by Let- 110 ters Patent, is.

In a fountain tooth brush of the charac-

ter described, comprising a handle adapted for the reception of a paste, and having a head with a transverse opening and a key-way, a plunger in the opening of said head, 5 a coiled compression spring normally pressing said plunger upward, a screw-threaded plug in the bottom part of the opening holding said spring in operative position, a plunger rod, a collar on said rod, the latter pro-

vided with a key and an operating knob on 10 said rod for operating said key for controlling the plunger to connect and disconnect communication between the handle and the brush.

In testimony whereof I have affixed my 15 signature.

LORENZ SOSDIAN.
